UNITED STATES PATENT OFFICE.

CHARLES F. HUMPHREYS, OF LANCASTER, PENNSYLVANIA, ASSIGNOR TO ARMSTRONG CORK COMPANY, OF LANCASTER, PENNSYLVANIA, A CORPORATION OF PENNSYLVANIA.

DESIGN FOR LINOLEUM OR OIL-CLOTH.

42,048.

Specification for Design.

Patented Dec. 26, 1911.

Application filed September 29, 1911. Serial No. 652,009. Term of patent 7 years.

To all whom it may concern:

Be it known that I, CHARLES F. HUMPHREYS, a subject of the King of England, residing at Lancaster, in the county of Lancaster and State of Pennsylvania, have invented a new, original, and ornamental Design for Linoleum or Oil-Cloth, of which the following is a specification, reference being had to the accompanying drawing, forming part thereof.

The figure illustrates a portion of linoleum, showing my new design, the remaining parts being duplicates thereof.

I claim—

The ornamental design for linoleum or oil-cloth, as shown.

CHARLES F. HUMPHREYS.
